UNITED STATES PATENT OFFICE.

GEORGE F. CARD, OF COVINGTON, KENTUCKY, ASSIGNOR TO HENRY K. LINDSEY, OF SAME PLACE.

CAR-BRAKE.

SPECIFICATION forming part of Letters Patent No. 334,637, dated January 19, 1886.

Application filed June 8, 1885. Serial No. 168,026. (No model.)

To all whom it may concern:

Be it known that I, GEORGE F. CARD, of Covington, Kenton county, Kentucky, have invented certain new and useful Improvements in Car-Brakes, of which the following is a specification.

My invention relates to improvements in those devices whereby—at any instant of time—the momentum of a moving car or train 10 can be utilized to retard or to stop it; and my invention consists in means by which the machinery for winding up the brakes becomes liberated for action by the disconnection or enfeeblement of an electro-magnet in a circuit 15 which is held normally closed. Such disconnection or enfeeblement is capable of being accomplished at any moment, for the whole train, by the engineer or other person controlling it through the instrumentality of a switch 20 or a rheostat in the circuit.

Rupture of the circuit accompanied by instantaneous setting of the brakes automatically ensues upon any one or more cars which become accidentally uncoupled from that part 25 of the train which remains attached to the locomotive. In the best forms hitherto devised for this purpose the major portion of the mechanical duty of setting the brakes is made to devolve on the running-gear of the car itself, 30 in association with a spring or weight, the duty of the electro-motive force being the comparatively light one of simply liberating these mechanically-acting members for operation.

In my present invention I secure a further 35 notable advance in economy of current by utilization, for the holding of the spring or weight out of action, of the same rotation of the axle as is made use of to wind up the brake-chain windlass. This object is accomplished 40 by the employment of an electro-magnet which encircles the axle, the latter acting as an armature, and whereby by the movement of such magnet through a small fraction of an inch in the act of grasping the axle the rotation of the axle itself becomes available to 45 overcome such spring or weight, so as to relieve the electro-motive force of that duty, and which has heretofore necessitated an armature movement of several inches, with a corresponding expenditure of current force.

In the accompanying drawings, Figure 1 is

a top view of a brake-operating mechanism embodying my invention. Fig. 2 is a vertical section on the line 2 2, the parts being in their normal condition and the brakes off. Fig. 3 55 is a similar section of the parts more immediately concerned in my invention, the brakes being set. Fig. 4 is a horizontal section on the line 4 4.

A may represent part of a railway-car 60 truck-frame. B may represent a track-wheel thereof. C may represent part of the axle of such wheel, and D a hub or collar thereupon, part of which hub constitutes one of the friction-wheels by which motion of the axle is 65 communicated to the brake-windlass.

E may represent part of any customary or approved system of brake-levers.

F may represent the customary chain or cable, which connects the brake-system proper 70 with the brake-windlass G. The brake-windlass G is journaled in a frame, H, one end of which is supported upon and secured to the axle C by any means that do not interfere with the axle's rotation—such, for example, as 75 straps I. The other end of said frame H is suspended from the truck-frame by hangers J.

Journalized in frame H by means of fulcrums K is a lever, L, whose lower portion (preferably of the represented bifurcated form) contains journal-bearings for the shaft M of a friction-wheel, N, of larger diameter than hub D, which wheel (when said lever L is pressed in direction of the dotted arrow, Fig. 2) bears against the periphery of the before-mentioned 85 smaller friction-wheel D, by which (should the train be in motion) it is rotated. The shaft M carries a pinion, O, that, remaining in permanent gear with a large spur-wheel, P, upon the brake-chain windlass G, causes 90 rotation of the latter, so as to wind up the brake-chain and to set the brakes. The transmitters D, N, O, P, and G have such relative diameters as to slow down the rotation at the windlass to about one-fifteenth that of the 95 axle, for the twofold purpose of securing great windlass-power, and of avoiding a too abrupt stretch of the brake-chain in the act of setting the brakes. A weight or spring, Q, connected by links R R and bell-crank S to the 100 lever L, imparts a constant tendency in said lever to move in direction of the dotted arrow,

so as to produce contact of the two friction-wheels *N* and *D*, and this tendency unless counteracted would operate to keep the brake mechanism permanently set. It is manifest that in actual use the precise reverse of the above conditions is required; or, in other words, it is necessary that while the brake mechanism should be capable at any given moment of prompt and certain action, its activity should, nevertheless, be held in a condition of normal suspense or abeyance. This has been hitherto accomplished in brake-operating devices of this kind by exerting a counter-pull upon the system of weighted levers by the direct action of the electro-magnetic armature, which has, consequently, required considerable length or amplitude of stroke with a corresponding expenditure of current. In my present invention, on the contrary, the pull upon the system of weighted levers is derived from the same member which drives the brake-windlass—namely, the car-axle—through the medium of an electro-magnetic clamp or clutch, whose demagnetization operates to liberate the weight for action. The movement of the parts of this clamp from a condition of activity to inaction, and vice versa, requiring to be only a small fraction of an inch, a comparatively feeble current is sufficient.

In my improvement the tendency of the lever *L* in direction of the dotted arrow, as aforesaid, is normally opposed and counteracted by the instrumentalities now to be explained: The hub *D* is of iron, and is sufficiently prolonged to take two embracing semi-annular jaws or yokes, *T*, hinged or linked to one another at *t*. Each jaw contains an electro-magnet, *U*, whose pole-pieces *u* are capable of being brought into close contact with the periphery of the hub *D*, and which are adapted to tightly grasp the latter the instant that the electro-magnetic circuit is completed, the hub *D* then acting as an armature to such magnets. On this taking place the electro-magnetic clamp *T* tends to be revolved in the same direction as that of the axle, so as to be carried to a position like that in Fig. 2, and would continue to revolve with the axle were it not brought to a standstill by reason of its connection—by rod *V* and bell-crank *W*—with the lever *L*. In consequence of this connection the drag in direction of rotation of the axle is transferred to said lever *L* in force sufficient to overcome that of the weight *Q*, and by holding the friction-gear apart to release the brakes.

It will be perceived that activity of the brake mechanism accompanies non-activity of the electro-magnet, and vice versa; hence a

lowering or weakening of the current through the instrumentality of a rheostat, *X*, (conveniently located for the use of the engineer or conductor,) by relaxing the grasp of the clamp *T*, permits the weighted lever *L* to put the friction-wheels *N* and *D* in mechanical contact, and to initiate brake action with force inversely proportionate to that of the current. It is furthermore apparent that through the same instrumentality the engineer may at any instant suddenly set the brakes by simply rupturing the circuit. It is further manifest that such complete and instant setting of the brakes of one or more cars will automatically accompany their accidental uncoupling from that part of the train which remains attached to the engine.

Each car may be provided with customary capstan, (not here shown,) to enable the forcible withdrawal of the brakes whenever desired.

The part *D*, which discharges the function of an armature to the electro-magnet *U*, may consist of an iron hub or collar shrunk or otherwise secured upon the axle, or it may be an integral part of the axle itself turned down to the proper shape and dimensions for that purpose.

An important modification of the within-described arrangement, in which any electro-magnetic clasp is utilized to produce instead of to suspend brake action, is the subject of a separate application for patent by me, Serial No. 186,737, filed 26th December, 1885, to whose specification reference may be made for more particular description of features common to both forms.

I claim as new and of my invention—

1. In a car-brake, in combination with a car-axle and brake-setting mechanism, a hub or collar on the axle, a clamp adapted to grasp said collar and mechanically connected with the brake-setting mechanism, electro-magnets for operating said clamp, a source of electricity, and a circuit including said magnets and source, substantially as set forth.

2. The combination, with a car-brake operated by momentum of the train, of the electro-magnet clamp *T*, which embraces a hub, *D*, on the axle, and has normal electrical connection with a rheostat, *X*, and mechanical connection with the system of weighted levers, which set the brake-windlass in motion, substantially as set forth.

In testimony of which invention I hereunto set my hand.

GEORGE F. CARD.
